WOVEN WIRE FABRIC

Raymond J. Guba, Philadelphia, Pa., assignor to
Audubon Wire Cloth Corporation, a corpora-
tion of New Jersey

Application November 9, 1937, Serial No. 173,562

8 Claims. (Cl. 245—6)

The invention relates to woven wire fabric and involves an improvement in means for hinging together adjacent helical coils of such a fabric and for providing wear resistant edges for such fabric when it is used for belting.

One of the primary objects of the invention is the provision of a hinging rod structure which is so designed that it serves not only as a hinge element between adjacent coil elements of the woven fabric, but is so constructed as to form wear resistant edges for the fabric when it is made up as a belt. The use of a hinge rod for the purpose of connecting the helical coils of a woven wire fabric is well known. It has also been suggested heretofore that one end of such a hinge rod be joined to the end of an adjacent hinge rod in such a manner that the rods of successive pairs are connected together at one end of the hinging unit. In such structures the unjoined ends of the rods which form the pairs are free to move laterally with respect to each other, so that the opposite edges of a belt constructed in this manner do not have the same degree of flexibility, resilience and stretch. Furthermore, such structures provide no means for preventing endwise movement of the hinge rods in one direction transversely of the belt. These disadvantages are overcome in the present improvement by rigidly connecting the adjacent ends of successive pairs of hinge rods so that each of the pairs of rods forms a rigid structural unit, and the rods are restrained against endwise movement thereof in both directions with respect to the belt.

Another object of the invention is the provision of a wear resistant edge for wire belting, so constructed that the wear thereon when the belt is in use does not affect the coil elements of which the woven fabric is made. With such a structure, the wear resistant elements may be made of a material which is more resistant to wear than the material of the coils, and they may be repaired or replaced at a cost much less than the cost of repairing or replacing the coils themselves.

A further object of the invention is the provision of a wear resistant edge for a wire belt, so constructed that one edge of the wear resistant element is positioned substantially in the plane of one surface of the belt in order to provide a continuous operating surface throughout the width of the belt.

Still further objects and advantages of the improvements will be apparent from the following

description, taken with the accompanying drawing wherein:

Fig. 1 is a plan view showing a section of belting made in accordance with the present invention, with a portion thereof broken away;

Fig. 2 is a side elevational view of the structure shown in Fig. 1;

Fig. 3 is a longitudinal sectional view taken on the line 3—3 of Fig. 1; and

Fig. 4 is an inverted plan view of one of the hinging units, partly broken away.

While the present improvements may be utilized with other forms of woven wire fabric and belting made therefrom, I have illustrated the same in the drawing in connection with a fabric in which the helical coils are of a composite character in that each coil element comprises two independent coils 10 and 11 of similar structure and threaded together in such a manner as to be confined within the same marginal limits. The adjacent ends of the two coils forming this composite structure are welded together as shown at 12 and 13 in order to provide a rigid coil unit in which each coil element is held against movement with respect to the other.

A plurality of such coil units are successively interwoven with each other to form a continuous length in a manner well understood in the art. As will be apparent from the drawing, the loop portions 14 of the turns of the coils 10 overlap and interengage with loop portions 15 of the coils 11 in the adjacent coil unit. It will also be apparent that loop portions 16 of coils 11 overlap and interengage with loop portions 17 of coils 10 in the adjacent coil unit. The loop portions of adjacent coil units overlap to such an extent as to provide openings 18 extending transversely of the fabric for receiving hinge rods 19. As is well understood in the art, the tension which is exerted upon the loop portions of one of the coil elements by an endwise pull upon a belt of this character is transmitted through the hinge rod, and not directly, to the interengaging loop portions of the adjacent coil elements, to thereby provide a more flexible belt structure.

The hinge rods 19 are not attached to the loops, but extend freely through the overlapping portions of the adjacent coil units and are thus freely movable with respect to the coils to provide a flexible hinge structure. Each of the rods projects outwardly beyond the opposite edges of the fabric as shown at 20. The adjacent ends of successive pairs of hinge rods are rigidly connected together by means of short bars 21 made of wear resistant material and having the oppo-

site ends thereof welded to the projecting ends 20 of the hinge rods as shown at 22.

The bars 21 are preferably of such a length as to extend laterally slightly beyond the hinge rods 19, and the lateral dimensions of the bars are preferably such that one edge 23 is positioned substantially in the plane of the operating surface of the belt as shown in Fig. 2. Inasmuch as the inner edges of the bars 21 are positioned 10 closely adjacent the end turns of the coil elements, endwise movement of the hinge rod units 24 and the hinge rods comprised therein, in a direction transversely of the belt, is prevented.

As will be apparent from the structure illustrated in the drawing, the hinge rods are entirely disconnected from the coil elements, thus providing maximum flexibility in a belt structure of this general type. As will also be apparent, each hinging unit is of rigid construction and 15 comprises a pair of hinge rods rigidly connected together at their ends, thus assuring the same flexibility and resiliency of the fabric along the opposite edges of the belt. Inasmuch as conveyor belts of this general type are usually subject to excessive wear along the edges, by reason 20 of frictional engagement with the guide elements with which they contact when in use, the edge portions of the belt are usually damaged much more rapidly than other parts. With the present improvement the damage can easily be remedied 25 by replacing one or more of the bars 21 or the hinge rods 19. This obviates the necessity of replacing the helical coils, which must be resorted to when the belt is so constructed that the ends 30 of the coil elements are subjected to wear by frictional engagement with guide members.

While a certain form of my improvement, together with the preferred arrangement of the various parts thereof, has been disclosed herein, 35 it is to be understood that the invention is not intended to be limited to the precise structure and arrangement of parts shown and described. The disclosure is therefore to be regarded as 40 illustrative only, and it is to be understood that 45 the invention is susceptible of embodiment in other forms and arrangements so long as they are within the scope of the appended claims.

What I desire to claim is:

1. A woven wire belt comprising a plurality of 50 interwoven helical coils having the turns of each overlapping and interlocking with the turns of adjacent coils to form a continuous fabric, a continuous hinge rod extending entirely through each coil between the turns thereof and the overlapping turns of each adjacent coil, and means 55 for rigidly connecting the ends of each rod with the corresponding ends of an adjacent rod.

2. A woven wire belt comprising a plurality of 60 interwoven helical coils having the turns of each overlapping and interlocking with the turns of adjacent coils to form a continuous fabric, a hinge rod extending entirely through each coil within the overlapping portions of adjacent coils, and wear 65 resistant bars rigidly secured to the adjacent ends of successive pairs of said rods and having one edge arranged substantially in the plane of one surface of said fabric.

3. A woven wire belt comprising a plurality 70 of interwoven helical coils having the turns of each overlapping and interlocking with the turns

of adjacent coils to form a continuous fabric, a hinge rod extending through each coil within the overlapping portions of adjacent coils and projecting slightly beyond the opposite ends of the coils, and means rigidly connecting the projecting ends of successive pairs of said rods to form wear resistant edges for said belt. 5

4. A woven wire belt comprising a plurality of 10 interwoven helical coils having the turns of each overlapping and interlocking with the turns of adjacent coils to form a continuous fabric, a straight, rigid hinge rod extending loosely through each coil within the overlapping portion of the turns of adjacent coils, and means for 15 rigidly connecting together the adjacent ends of successive pairs of said rods to form wear resistant edges for said belt and to prevent endwise movement of said rods in both directions with respect to said belt. 20

5. A woven wire belt comprising a plurality of 25 composite helical coils having the turns of each overlapping and interlocking with the turns of adjacent coils to form a continuous interwoven fabric, a hinge rod extending freely through each of said composite coils within the overlapping 30 portions of the pairs of adjacent coils, and wear 35 resistant bars rigidly connecting together the adjacent ends of successive pairs of said rods at opposite edges of said belt.

6. A woven wire belt comprising a plurality of 40 composite helical coils having the turns of each overlapping and interlocking with the turns of adjacent coils to form a continuous interwoven fabric, the adjacent ends of the wires forming 45 each composite coil being rigidly secured together, a hinge rod extending freely through each of said composite coils within the overlapping portions of the turns of adjacent coils, and wear 50 resistant bars rigidly connecting together the adjacent ends of successive pairs of said rods on both 55 edges of said belt.

7. A woven wire belt comprising a plurality of 60 composite helical coils having the turns of each overlapping and interlocking with the turns of adjacent coils to form a continuous interwoven 65 fabric, means for securing together the adjacent ends of the wires forming each composite coil, a hinge rod extending freely through each of said composite coils within the overlapping portions of the turns of adjacent coils, and means rigidly 70 connecting the adjacent ends of successive pairs of rods to provide wear resistant edges for said belt and to prevent endwise movement of said rods in both directions with respect to said belt. 75

8. A woven wire belt comprising a plurality of 80 composite helical coils having the turns of each overlapping and interlocking with the turns of adjacent coils to form a continuous interwoven fabric, the adjacent ends of the wires forming 85 each composite coil being welded together, a hinge rod extending freely through each of said composite coils within the overlapping portions of the turns of adjacent coils and projecting slightly beyond the edges of said belt, and wear 90 resistant bars welded to the adjacent projecting ends of successive pairs of said rods and preventing endwise movement of said rods with respect to said belt. 95
